UNITED STATES PATENT OFFICE.

WILLIAM P. WARE, OF ALDERSON, WEST VIRGINIA.

COMBINED TIE-PLATE AND RAIL-ANCHOR.

1,395,691.

Specification of Letters Patent.

Patented Nov. 1, 1921.

Application filed May 13, 1921. Serial No. 469,250.

To all whom it may concern:

Be it known that WILLIAM P. WARE, a citizen of the United States, residing at Alderson, in the county of Monroe and State of 5 West Virginia, has invented certain new and useful Improvements in Combined Tie-Plates and Rail-Anchors, of which the following is a specification.

The present invention relates to railways 10 and more particularly to a device for supporting rails on ties and for maintaining the rails from creeping particularly in the direction of travel.

An object of the present invention is to 15 provide a combined tie plate and anti-creeper or rail anchor which may be easily positioned in the laying of the rails and which may be simultaneously or subsequently used as a rail anchor.

20 Another object of the present invention is to provide a combined tie plate and rail anchor which comprises but two parts, a base section serving as a support for the rail and a wedge section serving as a binder for 25 wedging or binding the base of the rail upon the supporting plate and thus not only maintaining the rail against tilting and cutting the tie but also holding the rail from creeping incident to travel or to expansion and 30 contraction.

The above and various other objects and advantages of this invention will be in part described in and in part be understood from the following detailed description of the 35 present preferred embodiment, the same being illustrated in the accompanying drawings, wherein:—

Figure 1 is a top plan view of a combined tie plate and rail anchor constructed according to the present invention, the view showing a portion of a rail mounted on the plate.

Fig. 2 is a side elevation of the same.

Fig. 3 is an end view of the device showing the locking wedge or key in place, and 45 showing a section of rail mounted therein.

Fig. 4 is a fragmentary sectional view taken on the line 4—4 of Fig. 3, showing, enlarged, the wedge or key in position.

50 Fig. 5 is an inner end view of the wedge or key.

Referring to the drawings wherein like parts are designated by similar numerals of reference throughout the several views, 10 designates a rail of standard form provided 55 with a base flange 11 and the usual support-

ing web 12 upon which the ball or head of the rail is mounted.

According to the form of the invention shown in Figs. 1 to 5 inclusive, the tie plate comprises a flat body portion 13 constructed of suitable material and in any suitable manner as by forging and provided at one marginal edge portion and upon its upper side with an inwardly extending and overhanging flange 14 of suitable height and depth to engage over and snugly receive therebeneath the adjacent longitudinal edge portion of the base of the rail. This overhanging flange 14 is supported by the thickening of the metal stock of the body or plate 13 at said edge portion and the thickened portion of the stock is provided with an upwardly and outwardly facing or beveled edge 15 to facilitate insertion of claws or the like for the removal of spikes and also for the purpose of conserving material at such points as where excess of material is of a disadvantage.

This overhanging flange 14 extends throughout the length of the tie plate 13 and at the opposite side of the tie plate the same is provided with a similar inwardly extending and overhanging flange 16 extending from one end of the tie plate to a position substantially intermediate its ends where such flange 16 is discontinued to provide a space for a wedging key, as will be subsequently described. The opposite end portion of the tie plate 13 is provided with an upwardly enlarged or thickened portion 17 providing a way or retainer for the key and which extends from an overlapping position with respect to the flange 16 to the opposite end of the tie plate and which at its inner side is stepped outwardly from the flange 16 to provide a guiding edge 18 against which the key is adapted to slide. The inner face of the enlargement 17 is of wedge or cam form and extends downwardly and forwardly from the guiding edge 18 to the base of the enlargement 17 and provides an undercut wedging face complementary to a correspondingly formed wedging face 19 on the outer side of the key 20. The key 20 is in the form of a bar which is provided with an inner straight side having a recess 21 therein adapted to conform to and receive therein one longitudinal edge portion of the base 11 of the rail and the said key or wedge 20 being enlarged at its outer end to 110

provide a head 22 which terminates at its inner edge in a stop shoulder 23, adapted to abut against the adjacent edge of the tie plate 13. This shoulder head 22 extends 5 not only across the wedge face 19 thereof but also across the bottom of the key to leave a depending block 24 which abuts against the adjacent end of the tie plate and extends beneath the base 11 of the rail for 10 firmly gripping the rail base not only from above but also from beneath the same. The flange 16 extends vertically of the plate and is adapted to serve as a guiding surface for the introduction of the base of the rail beneath 15 the overhanging flange 14 and the guiding surface or flange 16 terminates in an abrupt stop shoulder 25 facing toward the flaring recess of the tie plate from beneath the wedge face 18, and receives there- 20 against the inner end of the key.

To the tie plate 13 may be secured a tie in any suitable manner but preferably by the usual spikes which are driven downwardly through openings 26 in the flanged 25 side of the tie plate and through an opening 27 in the guiding edge portion 16 of the tie plate and at the opposite side of the rail. Another spike, such as 28, is used as a locking pin for the wedge 20 after the 30 latter has been driven into place and for this purpose the tie plate is provided through its enlarged portion 17 with a recess 29 opening through the wedge face 18 and which is complementary to a recess 30 which 35 is formed vertically in the key 20 and which opens through the adjacent wedge face 19. These recesses 29 and 30, as shown in Fig. 4, are adapted to aline when the key or wedge 20 is in place and the pin or spike 28 40 is then adapted to be driven downwardly through the recess 29-30 and into the tie. It will be noted that by such construction no strain is placed upon the spike for holding the rail to the plate as the key or wedge 45 20 takes up all friction and retaining forces exerted between the plate and the rail having a tendency to separate the same.

The stop shoulders 25 and 23 are provided for the purpose of limiting the jamming and 50 distortion of the wedge or key 20 when driven in, and for determining the registration of the recesses 29 and 30.

The wedge or key 20, when being driven in begins binding against the rail base prior 55 to the seating of the stop shoulders 23 and 25, and the wedging action actually takes place during the final or seating movement of the key and is sufficient for taking up any inequalities found in the dimensions of the 60 parts, and is limited to prevent distortion of the same.

It is of course understood that various changes and modifications may be made in the details of construction and design of the 65 above specifically described embodiments of

this invention without departing from the spirit thereof, such changes and modifications being restricted only by the scope of the following claims.

What is claimed is:

1. In a combined tie plate and rail anchor, a body plate having an overhanging flange at one edge adapted to engage the base of a rail and having an upstanding shoulder at its other edge adapted to engage the opposite edge of the rail base, said shoulder having a recess therein near one end and extending from said end inwardly and having a downwardly and forwardly extending top wall providing a wedge face overhanging the body plate, and a key insertible longitudinally into said recess and having an inclined upper face providing a wedge face adapted to slide on said first wedge face, said key having near its outer end a stop shoulder adapted to engage the body plate shoulder thereof to limit the insertion of the key, said key also having a straight inner side with an undercut recess therein adapted to receive the adjacent longitudinal edge portion of the rail base, and said plate and key having complementary spike receiving recesses adapted to aline when the key is in place for locking the key in the plate. 70 75 80 85 90 95

2. A combined tie plate and rail anchor comprising a plate adapted to extend beneath a rail, said plate having spike receiving openings by means of which the plate may be fixed to a tie and having at one edge an overhanging flange to receive the edge of a rail base and a shoulder at its opposite edge adapted to receive thereagainst the opposite edge of the rail base, said shoulder of the plate being recessed near one end of the plate and the recess having an undercut outwardly flaring wall forming a wedge face and having a stop shoulder at the inner end of said face, a key tapered at one end and adapted to be driven thereat into the recess against said stop shoulder and having a complementary wedge face adapted to engage against said overhanging wedge face of the plate for advancing said key against the rail base, said key also having an outstanding shoulder on its outer end adapted to engage the plate to further limit the driving in of the wedge, said key having a recess in its inner edge portion adapted to receive the adjacent edge of the rail base and the latter being adapted to bind in said recess of the key as the latter is advanced into the recess of the plate, said plate and said key having complementary recesses opening through the wedge faces thereof for the reception of a locking member adapted to retain the key from displacement. 100 105 110 115 120 125

3. A combined tie plate and rail anchor comprising a body plate adapted to extend 130

beneath a rail and having an overhanging flange at one edge and an upstanding shoulder at its other edge for the reception of the base of a rail, a key adapted for insertion 5 between the flange of the rail and said shoulder of the plate and the latter being recessed to receive the key and the key and the plate having complementary wedging faces for advancing the key toward the rail 10 upon insertion of the key, said key having a head portion at its outer end forming a stop shoulder for limiting insertion of the key and the key having a longitudinal recess in its inner side to receive the edge of the 15 rail base, the recess extending through said head, said head having a portion adapted to extend beneath the flange of the rail.

4. A combined tie plate and rail anchor comprising a body plate adapted to extend

beneath a rail and having opposite portions 20 adapted to engage the base of a rail, said plate having a recess near one end opening toward the base of the rail and having an undercut outwardly flaring face defining the upper wall of the recess, and a key having 25 one end portion corresponding in cross section and length to said recess and provided with a complementary inclined tapering side wall adapted to engage the said wall of the recess for advancing the key toward the rail 30 base, said key having an engaging head on its outer end forming a stop shoulder adapted to engage the body plate and having a longitudinal recess through which the rail base is adapted to extend with a portion 35 of the head projecting beneath the rail base.

In testimony whereof I affix my signature.

WILLIAM P. WARE.
